ADJUSTABLE TRANSFORMER, PREFERABLY FOR CURRENT SUPPLY OF X-RAY INSTALLATIONS

Ole Lütz Hopermann, Charlottenlund, Denmark, assignor to Holger Andreasen, Copenhagen, Denmark, a Danish firm

Application January 30, 1957, Serial No. 637,212

2 Claims. (Cl. 336—147)

The invention relates to an adjustable transformer, preferably for current supply of X-ray installations and for a minimum line voltage, for example 110 volts, and at least one higher line voltage, for example 220, 380, 440 and 480 volts, and with fixed or adjustable taps, partly for means, for example for other transformers, which feed the X-ray tube with filament current and high tension, partly for the auxiliary devices of the installation such as relays and oil pump, and of the kind having an inner and an outer winding, both substantially uniformly distributed on an annular iron core, and in which the outer winding is accessible by means of at least one adjustable tap, for example a sliding contact resting against a stripped part of the outer winding or against a number of taps distributed along this winding, the outer winding being by means of the other tap divided into two winding sections of which the former has a substantially larger number of windings than the other winding section.

Transformers of the aforesaid kind are known and constitute a further development of the ordinary, known auto-transformers which have one winding only, uniformly distributed along the circumference of the iron core, and all its windings are accessible by means of a sliding contact resting against a stripped part of all the windings. It will be appreciated that if the outer terminals of the winding are connected to a line voltage, for example of 220 volts, the whole winding will act as an exciting winding, and the core will be uniformly energized along its whole circumference, and between the zero terminal of the winding and the sliding contact it will be possible to collect a variable voltage which in accordance with the position of the sliding contact may be varied approximately continuously from 0 to 220 volts. If, on the other hand, the auto-transformer is to be used in combination with a line voltage of 110 volts, the said voltage is connected between one outer end of the winding and a central tap, and the winding half located between these will energize the corresponding half of the core more intensely than the other half of the core. The voltage collected between the zero terminal of the winding and the sliding contact will in that case vary both in regard to intensity and in regard to shape of curve.

In extreme cases the voltage curve will reach a peak at the middle of each half cycle, which involves partly that the transformer yields a lower output than if the voltage curve was sinusoidal, and partly that such peaks may involve breakdown or puncture either in the transformer proper or in its connected members and devices.

In the known transformers of the aforesaid kind the inner and the outer winding are generally connected in series, and the outer winding is provided with a tap for connection to the lowest line voltage, for example 100 volts. Since it is generally desirable to have a possibility of regulating the collected voltage from abt. 70 to 220 volts, the tap for the lowest line voltage is not located at the point where the inner and the outer windings are joined, but in such manner that the outer winding is

2

divided into two winding sections, of which the former has a number of findings substantially larger than the other winding section. The exciting winding for the transformer will, when connected to 110 volts line voltage, consist of the whole inner winding plus the other winding section of the outer winding. Such part of the core as is located in the said other winding section is thus subjected to a more intense magnetization than the remaining part of the core, whereby similar phenomena in the shape of a distorted curve shape arise as mentioned above.

In other embodiments of known transformers of the aforesaid kind there is placed a so-called pre-coil at a limited area of the circumference of the annular iron core, preferably on the outer side of the inner and the outer winding. The said pre-coil is in series with the outer winding and is used when the transformer is to be connected to voltages higher than 220 volts, for example line voltages 380, 440 and 480 volts. Such a concentration of the exciting winding will likewise involve an irregular magnetization of the iron core and similar phenomena as mentioned above. In addition, the irregular shape of the divided winding and the pre-coil requires relatively large space, which again involves that the transformer has to be of larger dimensions than is desirable.

It is the object of the invention to devise the construction of an adjustable transformer of the aforesaid kind having none of the said drawbacks, and an essential feature of a transformer according to the invention is that the second winding section consists of a blindly terminated winding projecting from the other tap, the inner winding having a number $p+1$ winding sections, the ends of which lead to outer terminals and of which at least the winding sections p each have a number n of turns equal to the number of turns in the first winding section of the outer winding, whereas a winding section number $p+1$ is located at one end of the inner winding and has a number of turns equal to n times the ratio between the difference of the two highest line voltages and the lowest line voltage.

As a result, the transformer may by a simple change-over and interconnection of the inner and the outer windings be adapted for connection both to the lowest line voltage of 100 volts and to the higher line voltages of 220, 380 and 480 volts, and as a further result the exciting winding may in each of the cases mentioned be distributed substantially uniformly over the entire circumference of the iron core.

The invention will now be further described with reference to the drawing, in which

Figure 1 is a diagrammatic representation of an embodiment of an adjustable transformer according to the invention, in which the two windings of the transformer for the sake of clarity are shown as being arranged on either side of the symbol for the annular iron core of the transformer, whereas, in reality, they are disposed around the said core, one winding close to the iron core and the other winding on top of the first one.

Figures 2—5 are diagrammatical representations of other embodiments of the adjustable transformer according to the invention.

Figure 1 shows an adjustable transformer consisting of an inner winding 1 and an outer winding 2, both substantially uniformly distributed on an annular iron core 3, the outer winding being accessible by means of at least one adjustable tap 4 which may be a sliding contact or a carbon roller resting in contact with a stripped part or a number of taps distributed along the circumference of the outer winding. One end 5 of the inner winding is connected to a zero terminal 6 for the line voltage and the other end 7 is connected to a terminal 8 for the lowest line voltage, which, for instance, may be 110 volts, and

further to another tap, which in the embodiments shown in Figures 1-3 is a fixed tap, but may be an adjustable one, and which is placed on the outer winding, dividing the last mentioned winding into a first winding section 10 located between one end 11 of the outer winding and the other tap 9, and into a second winding section 12 located between the other tap 9 and the other end 13 of the outer winding. The one end 11 of the outer winding is passed to a terminal 14 which is used when the transformer is to be connected to a higher line voltage, for example 220 volts. The voltage range from which current is to be collected between the zero terminal 6 and the sliding contact 4, which is connected to a tap terminal 15, ranges normally in the installations for which the transformer is preferably intended, for example X-ray installations, between 70 and 220 volts, and a range of 70-110 volts can therefore be collected when the sliding contact 4 rests against the second winding section 12, whereas current may be collected from the range of 110-220 volts when the sliding contact rests against the first winding section 10.

When the transformer is connected to the lowest line voltage, for example 110 volts, its exciting winding will consist of the entire inner winding 1, and since the latter is uniformly distributed along the circumference of the iron core 3, the core will be uniformly energized along this entire circumference. If the transformer is connected to the higher line voltage, for example 220 volts, the exciting winding will consist of both the inner winding 1 and the first winding section 10 of the outer winding, whereas the second winding section 12 will not be incorporated in the exciting winding. The magnetization of the iron core will in that case not be so uniformly distributed over the circumference of the iron core as in the first mentioned case, but it is only a fraction, viz. $4\frac{1}{2}\%$ or about 18% of the circumference that will be magnetized by half the magnetizing power in proportion to the remaining part of the winding, and this difference of 9% in the magnetization has been found not to influence the curve shape of the collected voltages to any appreciable extent. This proportion is at any rate substantially more favourable than in the known transformers, which are distinguished from that disclosed thereby that connection between the terminals 7 and 9 is dispensed with and substituted by a connection between the terminals 7 and 13, a line voltage of 110 volts being in that case supplied across the terminal 9. The last mentioned method of connection has the result that when the known transformers are connected to a voltage of 110 volts between the terminals 6 and 9, 18% of the circumference of the iron core will not be subjected to any magnetizing power at all, which involves such an uneven distribution of the magnetization that it produces a material distortion of the curve shape of the voltage collected.

The voltage necessary for the auxiliary devices of the X-ray installation, such as relays and oil pump, is collected either across the terminals 5 and 7, if 110 volts is desired, or across the terminals 5 and 11, if 220 volts is desired for this purpose, and the said terminals may be connected to special connecting terminals for the auxiliary devices, for example, as indicated at the terminals 16 and 17. In the embodiment of the transformer according to the invention as shown in Figure 1 the inner winding 1 has a number of $p=3$ winding sections the ends of which are connected to the terminal 5 and a terminal 18, respectively, terminals 19 and 20 and a terminal 21 and the terminal 7, a fourth winding section, a $p+1$ th, which exists in the real transformer, being omitted for the sake of clarity, whereas the said winding section in the embodiment of the transformer according to the invention as shown in Figure 4 is disposed at the one end of the inner winding and has a number of turns determined by the ratio between the difference of the two highest line voltages and the lowest line voltage, and the said winding

section begins at the outer terminal 7 of No. p winding section and is provided with a free end terminal 22. No. $p+1$ winding section has relatively few turns, for example $4\frac{1}{2}\% n$ or $\frac{1}{4}n$, n being the number of turns in the first part 10 of the outer winding, and it is therefore of minor importance to the magnetization of the core whether this section is incorporated in the exciting winding or not, since it is only excluded when all the other exciting winding receive current, and the alternation will therefore only amount to $4\frac{1}{2}\% 40$, that is 9%.

With the three winding sections connected in parallel and the terminals 5, 19, and 21 being interconnected and connected to the line terminal 6, and the terminals 7, 18 and 20 being interconnected and connected to the line terminal 8, while the tap 9 is simultaneously connected to the terminal 5, it is possible to obtain as shown in Figure 2 that the transformer can be used for the lowest line voltage, for example 110 volts and with tapping for 220 volts between the terminals 17 and 16, of which the latter is connected to the terminal 7 or the terminal 18. The variable voltage 70-220 volts may as mentioned above be collected between the one end 11 of the outer winding, or its outer terminal 14, and the adjustable tap 4 or its outer terminal 15. In this combination the exciting winding consists of the three winding sections of the inner winding connected in parallel, and since these sections, apart from No. $p+1$ winding section which is omitted from Figure 2, are uniformly distributed along the circumference of the core, the core will be substantially uniformly energized along its entire circumference.

The adjustable transformer shown in Figure 2 may also be supplied with current from a 220 volts line if this is connected to the outer terminals 8 and 14, which does not bring about any change of conditions, neither in regard to the voltages collected across the terminals 16, 17 and 14, 15 or in regard to the magnetization of the iron core.

If, on the other hand, the transformer is to be used for a line voltage of 440 volts, the three winding sections of the inner winding are connected in series as shown in Figure 3, and this does not bring about any change of conditions in regard to the voltages collected and the magnetization.

In the embodiment of the transformer as shown in Figure 4 the third winding section 21, 7 of the inner winding of the transformer is provided in a manner known per se with a tap 23 dividing the said winding section in the ratio 5:6 and lying nearest the terminal 21. The tap 23 is connected to an outer terminal 24, and the free end terminal 22 of winding section No. $p+1$ is passed to another outer terminal 25. The transformer may thereby be connected to 380 volts line voltage between the outer terminals 14 and 24, 440 volts line voltage between the outer terminals 14 and 8 and 480 volts line voltage between the outer terminals 14 and 25.

In an embodiment of the transformer according to the invention the first winding section of the outer winding is provided with an extra turn 26 projecting from the end 11 of the outer winding remote from the other tap. Resting in contact with the windings near the said other tap 9 and near the said end 11 of the outer winding are other sliding contacts 27, 28 which contact stripped parts of the windings of the outer winding and are mechanically coupled in such manner that they may turn simultaneously in the same direction in relation to the circumference of the outer winding about such axis of symmetry of the iron core as is perpendicular to the plane of movement of the sliding contacts.

As a result, small variations in the nominal value of the line voltages supplied to the transformer may be equalised continuously, since a simultaneous turning of the sliding contacts 27, 28 has the effect that the number of turns in the outer winding between the said sliding contacts is kept constant, whereas the absolute voltage for the contact point of the one sliding contact with the outer winding

may be altered in relation to the zero point of the transformer. A special advantage obtained simultaneously is compensation on all voltages collected from the transformer at the same percentage value. In the known transformers such a compensation for variations from the nominal line voltages can only be made stepwise and furthermore with the disadvantage that the percentage alterations become unnecessarily high at the low line voltages and unjustifiably small at the high line voltages. The mechanical coupling of the sliding contacts 27, 28 may, for example as shown in Figure 4, be effected by attaching the sliding contacts to two arms 29, 30 emanating from a shaft 31 mounted in the axis of symmetry of the iron core, the said arms being coupled together so as to form an angle to each other by means of a member 32 and in such manner that there are a number of n windings between their points of contact with the outer winding.

The embodiment of the transformer according to the invention as shown in Figure 5 has a number of $p+1=5$ winding sections in the inner winding, that is, four uniform windings disposed respectively between the terminal 5 and a terminal 35, terminals 36, 33 and 34, 37 and a terminal 38 and the terminal 7. The transformer may be supplied with current either from the lowest line voltage, for example 110 volts, thereby that the one end 11 of the outer winding across its terminal 14 and the sliding roll 27 across its outer terminal 39 is connected to the zero terminal and the 110 volts terminal of the line voltage, respectively. The winding sections are connected in series by pairs and the two pairs are connected in parallel when the transformer is supplied with current from a 110 volts line. If it is desired to supply the transformer with current from a 220 volts line, the said voltage is fed through outer terminals 40, 41 leading to terminals 5 and 7, respectively.

It will be appreciated that the transformer disclosed in Figure 5 may be switched for use at line voltages of 380, 440 and 480 volts when all four winding sections are connected in series and the terminals 22 and 7 the tap 23 are connected to outer terminals for 480, 440 and 380 volts line voltage, respectively.

It will also be appreciated that the transformer disclosed in Figure 5 can be switched for use at a line voltage of 110 volts supplied at the outer terminals 40 and 41 when the p winding sections of the inner winding are connected in parallel. The transformer consists in this case of four uniform winding sections plus winding section No. $p+1$ and the outer winding which may be wound on top of the five inner windings, which, since all of them are incorporated in the exciting winding when the transformer is operating, may be either wound in such manner that each covers 90° of the circumference of the core or in such manner that each covers 360° of the circumference of the core; in the last-mentioned case they are placed in four concentric layers. In this case winding No. $p+1$ is disregarded; the importance of this winding to the magnetization is of substantially less value, and it may be dispensed with altogether if the transformer

is solely to be used for voltages which are an integer multiple of the lowest line voltage, for example 110, 220 and 440 volts.

If for reasons of safety it is a requirement that none of the outgoing wires of the transformer have more than 55 volts in relation to earth, the outer winding in the last-mentioned embodiment of the transformer may be connected to earth at its central point between the terminals 9 and 11.

Although only special embodiments of the adjustable transformer according to the invention are described in the foregoing, the protection should not be limited to the said embodiments, but only be limited by the claims.

What I claim and desire to secure by Letters Patent is:

1. An adjustable transformer, preferably for current supply of X-ray installations and for a minimum line voltage, for example 110 volts, and at least one higher line voltage, for example 220, 380, 440 and 480 volts, and with fixed or adjustable taps, partly for means, for example for other transformers which feed the X-ray tube with filament current and high tension, partly for the auxiliary devices of the installation such as relays and oil pump, and of the kind having an inner and an outer winding, both substantially uniformly distributed on an annular iron core, and in which the outer winding is accessible by means of at least one adjustable tap, for example a sliding contact resting against a stripped part of the outer winding or against a number of taps distributed along this winding, the outer winding being by means of another tap divided into two winding sections, of which the first one has a substantially larger number of windings than the other winding section, characterized in that the other winding section consists of a blindly terminated winding projecting from the other tap, the inner winding having a number $p+1$ winding sections the ends of which lead to outer terminals and of which at least the p winding sections each have a number n of turns equal to the number of turns in the first winding section of the outer winding, whereas a winding section No. $p+1$ is located at one end of the inner winding and has a number of turns equal to n times the ratio between the difference of the two highest line voltages and the lowest line voltage.

2. An adjustable transformer as claimed in claim 1, characterized in that the first winding section of the outer winding is provided with an extra winding projecting from such end of the outer winding as is located at the greatest distance of the other tap, other sliding contacts being provided on the turns of the outer winding near the other tap and near the said end of the outer windings, the said sliding contacts resting in contact with stripped parts of the outer winding, and being mechanically coupled in such manner that they are capable of turning simultaneously in the same direction in relation to the circumference of the outer winding about that of the axes of symmetry of the iron core which is disposed at right angles to the plane of movement of the sliding contacts.
